United States Patent Office.

IMPROVEMENT IN HAMMERS.

DAVID T. CROCKETT, OF NEWARK, NEW JERSEY.

Letters Patent No. 60,482, dated December 18, 1866.

The Schedule referred to in these Letters Patent and making part of the same.

TO ALL WHOM IT MAY CONCERN:

Be it known that I, DAVID T. CROCKETT, of the city of Newark, in the county of Essex, and State of New Jersey, have made certain improvements in an Implement for Housekeepers' Use; and I do hereby declare the following to be a full and exact description of the same, reference being herein had to the drawings accompanying this specification as being part thereof.

The nature of my improvement consists in forming of one piece of metal a combined hammer, screw-driver, and a tack-extractor, in a light, neat, and available manner.

In the drawings, A is the handle, B the hammer, C the screw-driver, and D the tack-extractor. The curve of the extractor resting on the fingers prevents the turning in the hand of the light, slim handle, which otherwise would have to be much heavier for the hand to grasp to steady the hammer-head, which needs to be of some weight. The position of the screw-driver gives such a firm hold that screws disproportionately large can be turned therewith. The whole is formed of one piece of metal.

I do not claim making the sides of the head even with the handle. What I claim, and desire to secure by Letters Patent of the United States, is—

A hammer, screw-driver, and tack-extractor combined, as shown, formed of one piece of metal, as a new article of manufacture.

DAVID T. CROCKETT.
